Application March 30, 1942, Serial No. 436,817

19 Claims. (Cl. 102—79)

(Granted under the act of March 3, 1883, as
amended April 30, 1928; 370 U. S. G. 757)

1

The invention described herein may be manufactured and used by or for the Government for governmental purposes, without the payment to me of any royalty thereon.

This invention pertains to a mechanical movement, to its application in a fuse and more particularly in a fuse for a rotating projectile.

An object of this invention is to provide a mechanical movement wherein a member is constrained to rotate about the path of recession of an opposed pair of centrifugal weight members.

Another object of the invention is to provide a fuse arrangement which is applicable for use in projectiles having high or relatively low speeds of rotation.

A further object of the invention is to provide a fuse having centrifugal members so connected to the firing mechanism that no centrifugal member can move to armed position without similar movement of the other.

An important object of this invention is to provide a fuse which will be armed only when a predetermined speed of rotation is reached thereby promoting bore safety.

An additional object of the invention is to provide a fuse having centrifugal members which are armed without the use of extraneous safety devices.

A still further object of the invention is to provide a fuse of the floating pin type operating on the centrifugal principle.

One of the principal objects of the invention is to provide a fuse which is simple in construction, inexpensive to manufacture, of a design adapted to mass production methods, reliable in its operation, and safe in handling.

To these and other ends, the invention consists in the construction, arrangement and combination of elements described hereinafter and pointed out in the claims forming a part of this specification.

A practical embodiment of the invention is illustrated in the accompanying drawing wherein:

Fig. 1 is an elevational view with parts in section of the front end of a projectile showing one type of fuse mounted therein;

Fig. 2 is a sectional view on the line 2—2 of Fig. 1;

Fig. 3 is a top plan view of the projectile delineated in Fig. 1;

Fig. 4 is a sectional view on the line 4—4 of Fig. 1;

Fig. 5 is an enlarged fragmentary view in perspective of certain of the fuse components;

2

Fig. 6 is a view in side elevation of the sealing cap of Figure 1;

Fig. 7 is a fragmentary view showing one manner of mounting a firing pin and hammer in a fuse-element;

Fig. 8 is a fragmentary sectional view representing another manner of mounting a fuse in a shell;

Fig. 9 is a sectional view at the nose of a shell which contains a modified fuse structure;

Fig. 10 is a sectional view on the line 10—10 of Fig. 9;

Fig. 11 is a partial sectional view of the front end of a projectile in which the fuse structure is secured within a sealing cap;

Fig. 12 is a sectional view on the line 12—12 of Fig. 11;

Fig. 13 is a transverse sectional view at the nose end of a projectile showing a fuse having a snap action;

Fig. 14 is a similar view of a modified structure;

Fig. 15 is an elevational view of the sealing cap which supports the fuse represented in Fig. 14;

Fig. 16 is a transverse sectional view through the nose end of a shell showing another fuse structure;

Fig. 17 is a perspective view of the combined cap and ring component of Fig. 16 which actuates the firing pin;

Fig. 18 is a longitudinal sectional view through the nose end of a projectile delineating a modified fuse;

Fig. 19 is a sectional view on the line 19—19 of Fig. 18;

Fig. 20 is a longitudinal sectional view of an additional modification;

Fig. 21 is a transverse sectional view on the line 21—21 of Fig. 20, and

Figs. 22—26 are sectional views of other fuse organizations; Fig. 25 being a transverse section on the line 25—25 of Fig. 24;

Fig. 27 is an elevational view with parts in section of the nose end of a projectile showing another modification of the invention;

Fig. 28 is an elevational view of the cap which fits within the cavity at the nose end of the projectile shown in Fig. 27;

Fig. 29 is a transverse section on the line 29—29 of Fig. 27;

Fig. 30 is a cross-section of the cap shown in Fig. 27 in a plane passing through the center of the cap and at right angles to the sectional plane of Fig. 27;

Referring to Figs. 1—6, there is shown a portion of the body 1 of a shell containing a charge

2 of high explosive and a primer cup 3 which is held within a bore 4 which communicates with the charge 2. The nose of the projectile is provided with a pair of concentric communicating recesses 5 and 6 which are of unequal diameters. Recess 5 has a larger diameter thereby providing an annular seat or step 7. Within this step and the body is a pair of diametrically disposed grooves 8 which are arranged to receive a pair of pins 9 that pass through the extended ends 10-10 of an elliptically shaped ring 11. Ring 11 is preferably a light metallic band which has a width several times its thickness for reasons which will be subsequently stated. The ring is disposed so that its width lies in a plane which is substantially parallel to the longitudinal axis of the shell. Spaced equidistantly about the ring and secured thereto are several weights 12 which may conveniently be rivets. A pair of vertically elongated rectangular holes 13-13 (Figure 5) is provided on diametrically opposite positions in the ring. These are arranged to receive a transverse bar 14 which carries centrally disposed firing pin 15. Bar 14 is made of flat metallic stock similar to ring 11 and is conditioned adjacent its ends 16-16 with 90° helical twists 17-17 which are more clearly illustrated in Fig. 5. The twists are imparted in opposite directions so that when the coating portions of the ring 11 simultaneously move outwardly the transverse bar 14 is rotated 90° and the firing pin is rocked to a position where its axis is vertical.

The pins 9 support ring 11 so that it is suspended in recesses 5 and 6. The bottom edge of the band is preferably spaced a very small distance from the bottom 18 of recess 6. Inserted in the recess 5 is a cup-shaped sealing cap 19 which is provided with a pair of slots 20 and a pair of lugs 21 which overlie the pins 9, the latter being seated in the pair of grooves 8 in the shell body. The lugs 21 hold the cap 19 against rotation relative to the shell body 1 and as a consequence prevent binding between the walls of slots 20 and pins 9 when the projectile is subjected to rotational forces. Cap 19 is secured in place by peaning over the outer circular edge 22 at the nose of the projectile. The length of the firing pin may be such that the point will just graze the primer in arming.

Fig. 7 shows a conical firing pin 15 having a reduced shank 23 which is press fitted in a hole 24 or spot welded to the transverse bar 14. A tubular cap 25 is conveniently pressed on the shank 23 which projects through the hole 24 in the bar 14 and forms a convenient hammer which is light in weight. This mode of attachment is merely suggestive, however, and may be modified in many ways.

The operation of the embodiment is as follows: When the shell is fired from a gun it is rotated by the rifling therein. Setback forces at first will prevent ring 11 from moving along bar 14 due to friction with the floor of the fuse cavity. After the projectile has left the gun and when a predetermined speed of rotation has been attained, centrifugal force is sufficient to urge the weights 12 outwardly away from the axis of rotation. These weights are provided to overbalance the effect of pins 9, but the band 11 may be so designed as to incorporate a weighted portion integrally. The effect is to distort the ring 11 from an oval shape toward or beyond the circular form. This pulls the reduced ends 10 and the associated pins 9 inwardly in the grooves 8. Simultaneously the rectangular holes 13 coat

with the twists 17 on the transverse bar to rotate it 90° thereby presenting the firing pin 15 in armed position in direct alignment with the center of the primer 3. The firing pin cannot be rocked beyond the unarmed position because of the 90° bends in the bar 14. When a target is struck, the cap 19 is pushed or crushed inwardly into engagement with the tubular cap or hammer 25 on the end of the firing pin and the pin is thrust into the primer thereby exploding the shell in the usual manner. In this modification, only a sharp thrust into the center of the cap will be effective since the ring 11 will, to some extent, resist deformation of the cap in the outer portions. Other modifications herein provide for more sensitive percussion.

It will be understood that other additional safeguards against spreading of the hoop while in the gun may be provided in various manners well known in the art if such be deemed necessary.

A particular feature of the invention is the position of the transverse bar 14 when the fuse is in the unarmed position. As shown in Fig. 5 the width of the bar lies in a plane which will resist bending at all times prior to firing and while the spinning projectile is being accelerated from the gun and before the effect of centrifugal force is sufficiently pronounced to overcome other forces and rotate the bar. When the firing pin is in the armed position, the transverse arm 11 can be readily bent axially of the projectile as a result of impact when the shell strikes its objective. The width of the bar is great while the thickness is small, thereby permitting the use of inexpensive flat stock which is easily and quickly formed into the necessary fuse elements, although this invention is not limited to flat stock or any particular screw mechanism for turning the firing pin. Furthermore, the effect of inertia during acceleration on the bar 14 creates sufficient friction between its lower edge and the slot 13 whereby spreading of the band 11 is prevented until cessation of the setback forces, whereupon the clearance is restored. This promotes bore safety.

The pitch of the twist 17 constitutes one factor having a bearing on the ease of the expanding movement of the band and can be utilized to determine the velocity of rotation necessary to arm the firing pin. It may be perceived that structures other than a slotted hoop and bar, for instance, those provided with threaded or other cooperating helical elements can be employed to accomplish the same result. However, the band organization is a preferred arrangement because of the obvious saving in time, material, and machinery involved in the manufacture, and due to the safety factor involved in utilizing a member affording a greater resistance to bending in one lateral dimension than in the other.

A slight clearance exists between the bottom edge of ring 11 and the base 18 of recess 6 to avoid any drag or friction therebetween which would hinder the expanding movement at the smaller diameter of the oval ring after setback forces have ceased and centrifuging commences. The primer 3 need have but a small opening beneath the firing pin to receive it when it is thrust back upon impact of the shell with the target. This will serve to prevent premature ignition by accidental hits near the gun.

While the fuse is illustrated as a nose fuse 75 the same structure can be employed in a base

detonating fuse, or in fact to align any component of any type of mechanical fuse.

The coacting ring and transverse bar organization provides extreme safety during the handling of the projectile. Careless or malicious handling of the shell will not detonate the device since in all cases the two halves of the band must move in opposite directions from the longitudinal axis of the shell to arm the fuse. This is an outstanding feature of the device since, if the shell is jarred, one arm will move out, but the other will move in the same direction and restrain the bar from turning. The proper coaction of the parts to arm the fuse is impossible except by centrifuging. Since safety during manufacture is a factor which must be considered, the use of a pair of diametrically disposed grooves 8 to receive the ring sustaining pins 9 is an important feature. This enables the ring supported firing pin organization to be slipped down into the recesses 5 and 6 from the nose of the shell without twisting the firing pin 15 so as to come into registration with the primer cup 3. This avoids fortuitous explosions during assembling operations.

Fig. 8 illustrates a band structure similar to Fig. 4 in which a pair of diametrically disposed holes 26 are bored into the body 1 of the shell to receive the pins 9. The sealing cap 19 is simply a cup-shaped member without any projecting lugs. Care must be exercised in mounting this fuse so that the firing pin does not come into engagement with the primer, when the ring is flexed to present the pins to the holes.

Figs. 9 and 10 represent a modified fuse organization in which the pins 9 are secured at two points on the smaller diameter of the oval ring 11. The more remote ends 10 of the ring engage the flat ends 16 that are disposed outside of the helical twists 17. The pins 9 bear against compression springs 27 which are seated in a pair of bores 28 in the shell body and center the ring 11. These and similar centering devices may also be used in the other modifications, or the primer face may be made of such size as to underlie the pin for any position thereof due to slight sidewise excursions of the hoop. In particular, the hoop may be steadied in its generally central position by mounting the twist bar in the shell with pins as in the modification of Figures 18 and 19. Centrifugal force causes the pins 9 which act as weights to fly outwardly against the resistance of the springs 27. This bends the ring into a somewhat circular shape and the coacting rectangular holes 13 and the twists 17 rotate the transverse bar 14 through 90° to arm the fuse. This arrangement is easily and comparatively safely mounted in a projectile since the required flexure will not rotate the bar. A disk 19 serves as a sealing cap and is held in position by the usual peening operation, or similar effective means.

In Figs. 11 and 12 there is shown a reliable, practical embodiment of the invention. A pair of U-shaped bands 29 are secured at their bends 30 to the inner wall of the cup-shaped sealing member 19 by a pair of fasteners such as set screws 31. The free ends or arms 32 are provided with the holes 13a which engage the transverse bar 14 inside of the helical twists 17. Corresponding arms on each band are in contiguous relationship. The entire centrifugal structure is conveniently housed in the cup 19 which is easily and without danger first fully assembled and

then inserted in the recess 5 in the shell. The sealing member 19 is of suitable diameter to slide freely in the recess 5. The depth of recess 5 is somewhat greater than the skirt portion of the sealing member 19 and has a centrally disposed cylindrical protuberance 33 in its base which contains the primer 3. The diameter of the protuberance 33 is somewhat greater than the span of the arms 32 of the bands 29 when the structure is in the inoperative or unarmed position as shown in Fig. 12. When the shell is fired, the arms fly outwardly, rotating the firing pin to arm it, and reach a position free of the protuberance 33. This enables the cup to slide downwardly into the recess 5 when the projectile strikes its objective and carry with it the firing pin. This structure is more sensitive on impact in that it is not necessary that the sealing member 19 be bent inwardly on impact to displace the firing pin axially and detonate the shell. This provision for movement of the cap may be made in the other modifications also. In modifications where the centrifugal units are fixed, there is no danger of falling off center, but it will be understood that the full hoop with slidable pins engaging the cap may also be used in the Figure 12 type.

It will be noted that slots 13a in the bands 29 must be made somewhat wider than the slots 13 in Figure 5 because in this case the bands move relative to one another and clearance must be provided to prevent binding. The binding effect may also be obviated by providing only a very small pitch to the bar twist so that it will function on a small travel of the centrifugal members. The latter, in such case may be made more resistant to deformation.

Fig. 13 represents a fuse having a snap-action. A ring 11 is conditioned with a pair of oppositely disposed and inwardly directed bent bows 34. When sufficient speed of rotation is attained the bows 34 fly outwardly with a snap action and arm the device. This ring, because of its particular configuration and properties, will maintain the shell in an armed condition even though the velocity of rotation decreases to the point where a fuse built in accordance with the other modifications would have become unarmed by rotating back to its original position as a result of decreased centrifugal force. The structure shown in Fig. 13 possesses added bore safety since it arms at rotational speeds which may be adjusted to a nicety.

Fig. 14 delineates a snap action fuse which is provided with a pair of spaced bars 35 which engage the transverse bar 14. Each arm has an inwardly bent bow 34 and the ends of these arms are fixedly anchored in spaced slots 36 in the skirt portion of the sealing cap 19. This provides an integral fuse structure which is readily inserted in the recess 5 in the shell in the usual manner although it will be understood that bars 35 may be attached in the projectile itself. The spaced bars employed in this modification are easier and cheaper to fabricate than the ring structures previously illustrated.

There is shown in Fig. 16 a sectional view of a projectile incorporating the modified arrangement of Fig. 17. Here the ring 11a is a part of the cap itself, and has a pair of diametrically opposite L-shaped cuts 37 made therein so as to permit the formation of two parallel flat wings 38. These wings have free ends 39 which lie against the shoulders 40 formed in cutting the L cuts. Opposed rectangular holes 13 cut in

these wings sustain the transverse bar 14 which carries the firing pin 15. The cap organization is mounted in the shell as shown in Fig. 16 with the bowed portions designated generally as 41 in contact with the cylindrical walls of the recess 5 and the free ends 39 of the wings 38 extending into a pair of spaced slots 42 in the shell body. The entrances 43 to these slots are flared outwardly on but one side of each slot. When the shell attains a predetermined velocity of rotation the wings 38 belly outwardly and through the intermediation of the slots 13 and the helical twists 17 arm the device. The enlarged entrances 43 to slots 42 facilitate the outward movement of the wings 38.

The simplicity of the Figure 16 modification will at once be apparent. Other than the cap usual in this type of projectile, the only separate part is the bar carrying the firing pin. The essential fuse structure is embodied in simple stamping operation performed on the cap and a twist of the firing pin bar. It will be understood that although a cap member is shown in Figure 16, a simple ring member of similar construction but without the top covering may also be employed separately in a projectile in place of the hoop members shown in other modifications. Likewise, by simple mechanical expedients, provision may be made to prevent return of the ends 39 into the slots 42 if it is desired to maintain the fuse armed after missing a target so as to be self-destroying. Wings 38 may be weighted to aid centrifuging.

It has also been contemplated that the wings 38 be cut somewhat shorter than is illustrated. In this case there would be no need for the slots 42 in the shell body since the free ends of the wings would not extend outside the ring 11a. This modification would arm under less force than that of wings 38 as shown. However, in such case the bar will move slightly in a horizontal plane, and account must be taken of this in locating the pin with respect to the primer.

Figs. 18 and 19 illustrate a modification in which the fuse components are mounted as a unit in the sealing cap or cup 19. The transverse bar 14 has its ends 16-16 riveted to or simply pinched in a pair of slots in pins 44 which are journaled in apertures 45 in the cap 19. A pair of telescoping U-shaped members 46 form the flyweights for the device. These are conditioned in the usual manner to engage the transverse bar 14 and are pulled outwardly by centrifugal force to engage the twists 17 and arm the fuse. The telescopic arrangement insures translational movement of the two bands 46 without binding with the bar.

In the structure represented in Figs. 20 and 21 the ring 11 is provided with a horizontal slot 13 which receives the transverse bar 14 which rests in a horizontal plane when the device is unarmed. This arrangement permits the use of a narrow band for ring 11 and hence a shallower recess 5. The firing pin 15 is a projection which is integral with and in the plane of the bar and was formed when the blank or bar was fabricated by a stamping operation. A notch 47 appears in the transverse bar and constitutes a weakened portion so as to enable the bar to be more easily deformed or bowed inwardly in its armed position when the shell strikes its objective. It will be noted that the provision of a firing pin on the side of the bar permits the horizontal positioning of the bar in the unarmed position and the use of a circumferentially ex-

tending slot in the band. Thus, the band may be made much narrower than the bar with the result that upon arming, the central portion of the bar will extend above the band and will be accessible to shocks on the cap prior to contact between the cap and the band, which contact would tend to form a barrier against flexing motion of the cap.

The modification shown in Fig. 22 has a pair 10 of wings 48 which are formed by cutting two pairs of parallel slits in the top of a cup-shaped sealing cap 19 and bending them downwardly and perpendicular to the top of the cap. These wings are provided with the usual vertically disposed rectangular slots 13 which support the transverse bar 14. Centrifugal force urges these wings 48 outwardly and arms the fuse. The end portions 16 of the transverse bar are provided with shoulder stops 49 which are conveniently formed by bending the ends 16 into a right angle. These stops keep the wings 48 from escaping the bar. Similar stops, if desired, can be used on any of the devices illustrated. A sealing disk 19' is preferably employed to render the 20 mechanism weatherproof. The entire cap unit including the firing pin shown in this embodiment is arranged to slide farther into recess 5 to actuate the primer when the wings 48 and the transverse bar 14 are in the armed position. The usual hammer 25 (e. g. see Figs. 1 and 5) may be provided to afford contacting relation between cap and firing pin when armed.

Fig. 23 shows a fuse similar to that of Fig. 22.

A cup-shaped sealing cap 19 is provided with a 30 centrally disposed hammer 50. The wings 48 are separate members and are secured within the cup or cap 19 by suitable means such as rivets 51. The whole cap structure does not have movement in the recess 5 on impact as does the fuse arrangement of Fig. 20. The firing thrust is obtained by movement of the hammer 50 when the top of the cap 19 is bent inwardly.

The fuses represented in Figs. 24-26 are characterized by their ability to operate at lower speeds of rotation. The sealing cap 19 of Fig. 24 includes an elongated hammer 50 which is secured thereto in any convenient manner. A cylinder 52 with a flanged portion 53 is positioned in recess 6 and on the shoulder 7 of recess 5. Wings 48 are formed by slitting the cylinder longitudinally to any convenient length thereof as at 54. These support the transverse bar 14 in a manner previously described. Centrifugal force from rotation carries these members outwardly (as shown in phantom) and arms the fuse. The long leverage of these wings enables the fuse to be armed at relatively low speeds of rotation.

The fuse of Fig. 26 renders unnecessary the use of a hammer of the character shown in the preceding embodiment. The cylinder 52 and its 60 wings 48 are formed in the previously described manner but the cylinder does not include the flange. This cylinder is mounted in an inverted position in the recess 6 as contrasted with the one in Fig. 25 and the wings 48 are directed inwardly. A cylinder of smaller diameter could be provided with the wings in normal position. Centrifugal force carries the wings 48 outwardly and rotates the transverse bar 14 to the firing position so that pin 15 is presented in alignment with the primer 70 3 which is supported in a cylindrical explosive container 53 that is threaded into the shell body 1 at the lower end of the recess 6. This fuse structure also features arming at lower speeds of rotation.

It will be apparent to one skilled in the art that any of the fuse structures described above can be easily arranged to serve as the arming means for a time fuse. While the modifications shown are confined to a member carrying a firing pin, it will be readily appreciated to those skilled in the art that any component of any mechanical fuse may be varied from unarmed to armed position by the mechanical principle embodied in this invention, that is to say, a member rotated into position by a twisting action engendered by centrifugal weights.

The invention does away with the need for an extra setback safety common to most fuses since it can only be operated by centrifugal force. Due to the interrelated centrifugal members and the nature of their coaction with the turn bar, they cannot arm the fuse by independent action or unidirectional effort. There must be a divergence. As far as I am aware, this is the first fuse having centrifugal arming members which do not require extra safety elements to hold the centrifugal members in safe position, which safety elements are mere impedimenta and perform no other function in the fuse. Furthermore, most of the known safety elements offer at least a possibility of accidental arming due to mishandling, which is obviated in the fuse of this invention, due to the employment of the novel principle of the helical member of opposite hands.

Figures 27 to 30 show a type of fuse incorporating additional safety features alluded to hereinbefore. In this modification the entire hoop and twist-bar assembly is resiliently mounted to allow the twist bar to recede into a slot on setback as a further bar to rotation and the said assembly will also recede on impact to aid in firing. In addition, both the hoop and twist-bar are pinned to the cap to maintain their symmetrical and central alignment.

The resilient mounting is afforded by leaf springs 54, which may be conveniently attached to the cap, engaging under pins 48 on the hoop 41 and underpins 44. A diametral slot 55 in the central boss 33 is dimensioned to receive the twist bar 44 on setback, and the top of primer 3 is preferably set somewhat below the bottom of slot 55. For the purpose of employing the safety slot 55, the hoop 41 in this case clears the central boss 33 in the normal position.

Due to the unusual shape of the cap shown, it may conveniently be molded of plastics, although other simpler caps may also be used employing the setback safety shown.

An outstanding feature of the invention is the ease of functioning. In contradistinction to the known mechanical fuses having moving parts, the amount of work involved in arming is surprisingly small. The moving part involved, that is, the twist bar does not move against parts other than the slot in the hand. For all practical purposes it is floating in space and merely has to turn over on its axis to arm. Thus it has the advantages common to the so-called "supersensitive" fuses, and yet possesses inherent characteristics of certainty and safety. Furthermore its inertia can be still further reduced by dimensioning and the use of light materials. Due to the small amount of work involved, the pitch of the twist can be made very small and thus the functioning can be varied within wide limits adapting the principle to all calibers and velocities. In very small calibers a fuse according to the invention can be designed which would resemble the fine parts of a watch and yet be effective.

Whereas, in the specification and claims the connection between the centrifugal members and the body to be turned is variously referred to, and especially as a "twist" it will be understood that any equivalent mechanical connection which will convert the translatory motion of the centrifugal members into a turning motion of the firing parts on an axis directed in the path of recession of the centrifugal members may be used and is understood to come within the meaning of the word "twist."

I claim:

1. A fuse comprising a bar of rectangular section, twists of opposite hand in said bar, a hoop member having diametrically opposed openings slightly larger than the section of said bar and receiving the same, and a firing component on said bar and extending transversely thereto.
2. A fuse as in claim 1 wherein the cross section of said bar is of unequal dimensions and the openings in said hoop have their long dimension at an angle to the plane of the hoop.
3. A fuse as in claim 1 wherein the cross section of said bar is of unequal dimensions and the openings in said hoop have their long dimension in the plane of the hoop.
4. A fuse comprising a bar of rectangular section, twists of opposite hand in said bar, a hoop member having diametrically opposed openings slightly larger than the section of said bar and receiving the same, a firing component on said bar and extending transversely thereto, and diametrically opposed means on said hoop for engagement with the inner walls of a projectile.
5. In a projectile having a nose opening, a fuse in said opening comprising an ellipsoidal hoop, diametrically opposed pins on said hoop on the line of the major axis thereof, slots in the wall of said projectile, said pins being received in said slots, a cap covering said opening and having ears in said slots overlying said pins, diametrically opposed slots in said hoop on the line of the minor axis thereof and parallel to the axis of the projectile, a bar received in said slots, twists of opposite hand in the bar outside said hoop, and a firing pin extending from said bar laterally of the projectile axis when the fuse is in unarmed position with the hoop inside the twists.
6. In a fuse as in claim 5, weight members carried by said hoop to overbalance said pins centrifugally.
7. In a fuse as in claim 5, a hammer member on the side of the bar opposite the firing pin and aligned therewith.
8. In a projectile having a nose opening, a closed bottom in said opening, a central protuberance on said bottom, a fuse comprising an ellipsoidal loop member with minor axis lying within the area of the protuberance, a closure cap for said opening spaced from the bottom of said opening, said loop member engaging said cap at the extremities of its major axis, diametrically opposed slots in said loop member on the line of its minor axis, a bar received in said slots, twists of opposite hand in said bar outside said loop, and a firing pin on said bar extending therefrom laterally of the projectile when in the unarmed position with the loop inside the twists in the said bar.
9. In a projectile having a nose opening, a fuse comprising a cap member for said opening, spaced cross members attached to said cap, mutually directed bights centrally of said cross mem-

bers, slots in said bights, a bar received in said slots, twists of opposite hand in said bar outside said bights and a firing pin on said bar and extending laterally therefrom.

10. In combination, opposed centrifugal units, means constraining said units to a radial path of flight without rotation about the general line of said path, a cross member of oblong transverse section extending between said units, and spiral means of opposite hand on said member slidably received, respectively, in openings in said units, said openings being complementary to said spiral means whereby the member is turned about an axis in the general direction of the path of recession of the units upon centrifuging the latter.

11. In a projectile, a fuse comprising a firing component and a beam type carrying member having the said component fixed thereon, said carrying member having a high ratio of length to cross-sectional dimensions and a high ratio between the cross-sectional dimensions whereby flexure is rendered more facile along one of the transverse directions of the carrying member than along the other, a second firing component in the projectile, means for mounting said carrying means with its direction of less facile flexure aligned with the said second firing means, and means to adjust the carrying member to position where its direction of more facile flexure is aligned with the said second firing means.

12. A fuse comprising a housing, a beam member having helical paths of opposite hand pivoted in said housing for rotation and for translation longitudinally of said housing, receiving means for said beam member in the path of translation thereof to prevent rotation of said beam member in one extreme position of its translation, resilient means biasing said beam member away from said receiving means, and centrifugal means received on said beam member, and having means complementarily engaging said helical paths, and held against rotation about the axis of said helical paths.

13. A fuse comprising a member of oblong transverse section carrying a firing component and mounted for rotation about an axis radially of the fuse axis to rotate the firing component from safe to armed position, mass means positioned in the fuse for radial recession along said first axis on rotation of the fuse, and a connection between said mass means and said member constructed and arranged to turn said member to armed position of said firing component in response to recession of said mass.

14. A fuse comprising a bar of oblong transverse section, helical twists of opposite hand on said bar and centrifugal weight means mounted on said fuse for rotatively constrained translatory motion generally away from the axis of the fuse and having guide means located for engagement with the said twists at points offset from their axis of helix whereby the twists act as followers to rotate the bar on centrifuging of the weight means.

15. A fuse comprising an elongated member of oblong transverse section, oppositely threaded helical paths on said member, centrifugal weights slidably received on said elongated member, means in the fuse constraining said weights substantially to a single degree of freedom of mo-

tion with respect to the fuse bearing a substantial component transverse of the fuse, and guide means on said weights engaging the helical paths at points offset from their axis whereby to occasion rotation of the helices substantially about their axes by virtue of the single degree of freedom of motion of the weights.

16. A fuse comprising an elongated member, helical paths of opposite hand on said elongated member, a firing component carried by said elongated member and extending transversely thereto, and centrifugal weight means comprising a hoop with openings dimensioned to engage a portion of said spiral paths in a manner complementary thereto, said hoop arranged for motion of its portions bearing the openings in a direction generally transverse to the fuse axis whereby to turn the elongated member on flexing of the hoop, and means to mount the hoop in a projectile for rotation therewith.

17. A fuse comprising opposed centrifugal members, and a firing component of oblong transverse section extending between and slidably received in said members and transversely of the fuse, thread connections between said component and said members, of opposite hands, respectively, and means constraining said members to motion radially of the fuse only, whereby, as the members recede from each other the component is forced to revolve about an axis defined by the path of recession of said members.

18. In combination, opposed centrifugal units, means constraining said units to a radial path of flight without rotation about the general line of said path, a cross member of oblong transverse section extending between said units and slidably received therein, and a connection between said member and said units comprising cam and follower means constituting a couple with respect to the longitudinal axis of the cross member whereby the latter is constrained to rotate about an axis directed in the line of recession of said units on centrifuging thereof.

19. A fuse comprising an elongated firing component, opposed centrifugal means received on said component, cam and follower means between said component and said centrifugal means constructed and arranged to produce a turning couple on said component about its longitudinal axis on recession of said centrifugal means, and means to prevent turning of said component while subject to setback forces.

WILFRED E. THIBODEAU.
